UNITED STATES PATENT OFFICE.

JONATHAN LUCAS, OF SAVANNAH, GEORGIA, ASSIGNOR TO LUCAS-LAMBORN LOOM CORPORATION, OF NEW YORK, N. Y., A CORPORATION OF NEW YORK.

LOOM.

Original application filed May 7, 1924, Serial No. 711,581. Divided and this application filed February 15, 1927. Serial No. 168,257.

My invention relates to looms and has for its object to provide an efficient shuttle operating mechanism constructed and arranged to actuate the shuttle throughout all of its operative movements in a novel and improved manner. A further object of the invention is to provide a novel coupling mechanism whereby the shuttle is automatically connected with and disconnected from the shuttle operating mechanism in a novel and efficient manner at the proper points in the operative paths of said shuttle. Other more specific objects of the invention will appear from the description hereinafter, the features of novelty being pointed out in the claims. The present application is a division of another application filed by me in the United States Patent Office on May 7, 1924, Serial No. 711,581.

In the accompanying drawings, which illustrate examples of the invention without defining its limits, Fig. 1 is a front elevation of a loom embodying the invention and Fig. 2 is a diagrammatic view illustrating the invention on an enlarged scale.

The loom comprises a support 15 of conventional construction and suitable form provided with guiding devices upon which the reciprocating elements of the shuttle operating mechanism are guided in their operative movements. In the construction shown in Fig. 1 the guiding devices referred to, consist of a plurality of rollers 16 and 16^a arranged in spaced upper and lower series and journalled upon suitable portions of the frame 15. The rollers 16 and 16^a in each series are located at spaced intervals, throughout the paths traversed by the shuttle in its operative movements, and serve as guides for travelling carriers 17 and 17^a which are arranged to be reciprocated upon the rollers 16^a and beneath the rollers 16 as clearly shown in Fig. 1.

The mechanism whereby the carriages 17 and 17^a are moved toward and away from each other from one extreme position to another, may be of any suitable type and, as shown, may comprise a pair of rocking arms 18 pivoted at 19 upon the frame 15 and connected, at one end by means of links 20, with the carriers 17 and 17^a respectively. The other ends of said rocking arms 18 are connected, by means of connecting rods 21 with oppositely disposed cranks 22 forming

part of a crank-shaft 23 journalled on the frame 15. The shaft 23 carries a pinion 24 which meshes with a gear 25 fixed upon a counter-shaft 26 also journalled on the frame 15 and operated and controlled in a convenient manner to bring about an operation of the loom.

The carriers 17 and 17^a are each provided with supporting means for the shuttle, which means may comprise fingers 32 and 32^a located in pairs respectively upon said carriers 17 and 17^a, and projecting toward each other. The fingers 32 are located in a plane different from that in which the fingers 32^a are positioned and said fingers are preferably of such length as to overlap in the extreme innermost positions of the carriers 17 and 17^a. Each pair of fingers 32 and 32^a is constructed and arranged to extend along opposite sides of the shuttle 33, or in other words to straddle the same from opposite directions, and to project between flanges 34 suitably located upon the opposite longitudinal sides of said shuttle 33. The arrangement is such that the latter is carried alternately by the fingers 32 and 32^a and conveyed thereby over its operative paths. In addition, the carriers 17 and 17^a, which are reciprocated from extreme inner positions to extreme outer positions by the action of the mechanism previously described are provided with electro-magnets 35 and 35^a respectively. The electro-magnets are connected by electric circuits 36 and 36^a with contact members 37 and 37^a which cooperate with a rotary switch member 38 electrically connected with a battery 39 forming part of the circuits 36 and 36^a. It will be understood that the shuttle 33 is constructed in a manner to properly cooperate with the electro-magnets 35 and 35^a.

As the carriers reach their extreme inner positions, as illustrated in Fig. 2, the switch member 38 will have reached a position in which one of the circuits 36 or 36^a is closed; in the illustration in Fig. 2, the circuit 36 is the active one so that the electro-magnets 35 are electrically energized and consequently are in magnetic engagement with the shuttle 33 and accordingly attract and hold the same. As the operation of the loom now continues, the shuttle will be drawn toward the left in Fig. 2, by the action of the carrier 17 and the coupling connection between said

shuttle and the electromagnets 35, this connection is maintained until the carriers are back again in their extreme inner positions whereupon the switch member 38 will have reached the position in which the circuit 36^a is closed, the circuit 36 at the same time being broken. The electromagnets 35^a now become energized and consequently are in magnetic connection with the shuttle 33, which as a result is drawn toward the right as the carriers 17 and 17^a again move toward their extreme outer positions. This energizing and deenergizing of the electromagnets 35 and 35^a in alternate sequence and the consequent connection with and disconnection of the shuttle 33 in corresponding alternate sequence continues throughout any given period of operation of the loom.

In the form illustrative in Figs. 1 and 2, a positive connection is maintained between the shuttle and the actuating mechanism, through the entire operative paths of said shuttle. That is to say, throughout half of a given path in one direction and a half of a given path in the return direction, the shuttle is in positive connection with one carrier and throughout the other half of said paths, is in positive connection with the other carrier. The shuttle is thus positively controlled throughout its entire range of movement and consequently is uniformly moved and is free from undesirable variations in speed and at the same time is positively maintained in its intended paths.

The loom as usual includes harness mechanism operating in a manner to provide the shed of warp threads through which the shuttle is passed by the mechanism illustrated and described and to reverse the threads in said shed in the well known way. In addition the loom may include all instrumentalities customarily found in looms and operating in proper sequence to perform their various functions.

Various changes in the specific form shown

and described may be made within the scope of the claims without departing from the spirit of my invention.

I claim:

1. A shuttle shifting and carrying mechanism for looms comprising a pair of longitudinally movable carriers, means for inversely reciprocating the carriers in a transverse manner, a pair of fingers carried by each carrier, the fingers of one carrier being disposed in a plane different from that in which the fingers of the other carrier are located, a shuttle guiding means upon said shuttle adapted to receive the fingers of each of the carriers simultaneously, and electro-magnetic devices on said carriers for coupling the shuttle thereto, and switching means whereby said electro-magnetic devices are energized and de-energized in alternate sequence to disconnect one carrier from and connect the other with, said shuttle and vice versa. 50 55 60 65

2. A shuttle shifting and carrying mechanism for looms comprising a pair of longitudinally movable carriers, means for inversely reciprocating the carriers in a transverse manner, a pair of fingers carried by each carrier, the fingers of one carrier being disposed in a plane different from that in which the fingers of the other carrier are located and arranged to overlap in the innermost position of the carriers, a shuttle guiding means upon said shuttle adapted to receive the fingers of each of the carriers simultaneously, and electro-magnetic devices on said carriers for coupling the shuttle thereto, and switching means whereby said electro-magnetic devices are energized and de-energized in alternate sequence to disconnect one carrier from and connect the other with, said shuttle and vice versa. 70 75 80 85

In testimony whereof I have hereunto set my hand.

JONATHAN LUCAS.
